(57) **CLAIM**

The ornamental design for a camera, as shown and described.

DESCRIPTION

FIG. 1 is front, top and right side perspective view of a camera showing my new design;

FIG. 2 is a right side elevational view showing the design for the camera of FIG. 1;

FIG. 3 is a left side elevational view showing the design for the camera of FIG. 1;

FIG. 4 is a front elevational view showing the design for the camera of FIG. 1;

FIG. 5 is a rear elevational view showing the design for the camera of FIG. 1;

FIG. 6 is a top plan view showing the design for the camera of FIG. 1; and,

FIG. 7 is a bottom plan view showing the design for the camera of FIG. 1.

The broken lines in the drawings are shown to illustrate the portions of a camera in which the design is embodied and form no part of the claimed design.
